UNITED STATES PATENT OFFICE.

CATHERINE LAMBERT O'LEARY, OF ROSLYN HEIGHTS, NEW YORK.

DESIGN FOR A SYMBOLIC HAT.

49,618.

Specification for Design.

Patented Sept. 5, 1916.

Application filed May 4, 1916. Serial No. 95,514. Term of patent 3½ years.

To all whom it may concern:

Be it known that I, CATHERINE L. O'LEARY, a citizen of the United States, and a resident of Roslyn Heights, in the county of Nassau and State of New York, have invented a new, original, and ornamental Design for a Symbolic Hat, of which the following is a specification, reference being had to the accompanying drawing, forming part thereof.

Figures 1 and 2 are top perspective views of the hat seen from opposite sides and showing my design.

I claim:

The ornamental design for a symbolic hat, as shown.

CATHERINE LAMBERT O'LEARY.
